STENCIL HAWK

Walker J. Weesner, Indianapolis, Ind.

Application March 8, 1939, Serial No. 260,542

9 Claims. (Cl. 72—128)

(Granted under the act of March 3, 1883, as
amended April 30, 1928; 370 O. G. 757)

The invention described herein may be manufactured and used by or for the Government of the United States for governmental purposes without the payment to me of any royalty thereon 5 in accordance with the provisions of the act of April 30, 1928 (Ch. 460, 45 Stat. L. 467).

This invention relates to waterproofing masonry walls, but more particularly the brick walls of buildings, and the invention has for its object 10 to provide simple, cheap and durable "stenciling hawks", by means of which the waterproofing grout may be quickly applied to the mortar joints of a brick wall in a highly efficient, effective and economical manner, so that upon completion of 15 the waterproofing operation, the wall is left with an improved smooth and finished appearance and without the necessity of any cleaning or removal of excess grouting material therefrom.

With this object in view, the invention consists 20 of the novel construction and arrangement of the stenciling hawks, which for convenience of operation and most satisfactory results, should be used in pairs in the manner of and for the purposes hereinafter described.

25 Referring to the accompanying drawings:

Fig. 1 is a plan view of one of the pair of stenciling hawks used in the operation of waterproofing the horizontal joints between the courses of a brick wall.

30 Fig. 2 is a vertical sectional view through the same.

Fig. 3 is a plan view of the other one of the pair of stenciling hawks used in the operation of waterproofing the vertical joints between the 35 bricks.

Fig. 4 is a vertical sectional view through the same.

Fig. 5 is a plan view illustrating the application 40 to a brick wall of the stenciling hawk shown in Fig. 1, and

Fig. 6 is a similar view showing the application to a brick wall of the stenciling hawk shown in Fig. 3.

Like numerals of reference indicate the same 45 parts throughout the several figures, in which:

1 indicates the stenciling hawk shown in Fig. 1 which I will designate as the horizontal hawk and 2 indicates the stenciling hawk shown in Fig. 3, which I will designate as the vertical 50 hawk.

On each of the stenciling hawks 1 and 2 there is provided a metallic trough 3 for the reception of the grouting material, which is of a consistency sufficiently fluid to permit its application to the 55 masonry joints by means of a stiff brush.

Extending upwardly from this trough 3, and preferably integral therewith is a flat metallic back-member 4. Suitable ends 5 are provided for the troughs 3, and I prefer to provide a suitable bead 6 at each of the vertical edges of the hawks 5 for the purpose of stiffening the structures.

In the horizontal hawk 1 (Fig. 1) there is provided a longitudinal horizontal open slot 7 in the flat back-member 4 which slot extends through nearly the entire width of the back-member 4; 10 that portion of the material at the ends of the slot 7 being provided with a rear-way extending bead or crimp 8.

Arranged on the front and rear sides of the back-member 4 and along the horizontal edges 15 of the slot 7 are two flexible rubber strips 9, the edge portions of which slightly overlap the top and bottom edges of the slot 7, as shown in dotted lines in Fig. 1.

The vertical stenciling hawk 2 (Fig. 3) is provided in its back-member 4, with two horizontal rearwardly extending beads or crimps 10 and 11, spaced apart a distance equal to that of the 20 mortar joints between two courses of brick, while centrally of the back-member 4, is an oblong 25 opening 12 which extends from the center line of the upper bead or crimp 10 to the center line of the lower bead or crimp 11. Suitably secured to the rear surface of the back-member 4 is a 30 small flexible rubber sheet 13 having a vertical slot 14 provided therein, the edge-portions of which sheet adjacent its slot 14 overlap the vertical edges 15 of the oblong opening 12 in the metallic back-member 4.

The widths of the horizontal opening between 35 the two rubber strips in Fig. 1, and of the slot in the rubber sheet 13 in Fig. 3 is equal to the widths of the horizontal and vertical mortar joints between the bricks, while each of the stenciling hawks is provided centrally of their troughs 3 40 with a depending handle 16, for convenient support and correct positioning of the hawks by the hand of the artisan using them.

Having thus described the construction of the 45 stenciling hawks, the manner in which they are used in the application of waterproofing grout to the joints of brick walls is as follows:

A quantity of suitable waterproofing grout is placed in the trough 3 of the stenciling hawk 1, and the hawk is placed against the surface of 50 the wall 17, as shown in Fig. 5, so that the beads or crimps 8 therein register in the horizontal mortar joint 18 of the wall. This aligns the horizontal slot 7 of the hawk with the horizontal mortar joint so that the entire joint within the 55

length of the slot 7 is exposed, but the contiguous surfaces of the bricks are covered by the back-member of the hawk. When in this position, grout contained in the trough 3 is brushed into the mortar joint which is exposed through the slot 7. By reason of the flexible rubber pieces 9 at the top and bottom edges of the slot 7, a close contact is preserved at the adjacent edges of the bricks sufficient to prevent the grout from running down behind the back-member of the hawk and over the surface of the bricks. By this construction the surplus grout from the stiff brush is caused to run down the outer face of the back-member and into the grout trough 3, thus conserving the grout and obviating all waste. The hawk is moved along the horizontal joint as fast as the grout can be brushed in.

When using the vertical hawk 2, it is similarly placed against the wall surface so that the two horizontal beads or crimps 10 and 11 thereof register with two horizontal mortar joints 18, and the vertical slot 14 thereof uncovers a vertical mortar joint between two bricks. The grout is then similarly applied with a stiff brush and brushed into the joint. Similarly the flexible rubber in which the vertical slot 14 is formed provides a close contact with the adjacent faces of the bricks sufficient to prevent the grout from running down behind the hawk and over the surface of the bricks. Likewise the surplus grout from the stiff brush is caused to run down the outer face of the hawk and into the grout trough. The hawk is moved from joint to joint in order to complete the application of the grout to the vertical joints in the wall.

Having thus fully described the use of the stenciling hawks in the application of waterproofing grout to the horizontal and vertical mortar joints of a wall, I do not wish to be understood as confirming myself to the exact construction of the hawks as illustrated in the drawings and described herein, since such illustration and description is only intended to disclose what I consider to be an example of a simple and satisfactory construction. Various changes, alterations and modifications may be made in the construction and arrangements of the parts without departing from the spirit of the invention, and I consider myself clearly entitled to all of such as fall within the limit and scope of the appended claims.

I claim:

1. A stenciling hawk for use in the application of waterproofing grout to the joints of masonry walls and the like, which includes a grout-holding trough, a back-member extending upwardly from the grout-holding trough, the back-member being provided with a longitudinal open slot and two rearwardly extending beads in longitudinal alignment with said slot, and two pieces of flexible material on the back-member, the contiguous edges of which flexible pieces extend beyond the longitudinal edges of the said longitudinal slot.

2. A stenciling hawk for use in the application of waterproofing grout to the joints of masonry walls and the like, which includes a grout-holding trough, a back-member extending upwardly from the grout-holding trough, the back member being provided with a longitudinal open slot and two rearwardly extending longitudinal beads in longitudinal alignment with said slot, and two pieces of flexible material on the back-member and extending along the longitudinal edges of the said longitudinal slot.

3. A stenciling hawk for use in the application of waterproofing grout to the joints of masonry walls or the like, which includes a grout holding trough, a back-member extending upwardly from the grout-holding trough, the back-member being provided with a longitudinal open slot and including means for aligning the longitudinal open slot with a joint in a masonry wall or the like, and an edging of flexible material on the back-member extending along the longitudinal edges of the said longitudinal slot.

4. A stenciling hawk for use in the application of waterproofing grout to the joints of masonry walls and the like, which includes a grout-holding trough, a back-member extending upwardly from the grout-holding trough, the back-member being provided with a longitudinal open slot, and including means for aligning the longitudinal open slot with a joint in a masonry wall or the like.

5. A stenciling hawk for use in the application of waterproofing grout to the joints of masonry walls or the like, which includes a grout-holding trough, a back-member extending upwardly from the grout-holding trough, the back-member being provided with a longitudinal open slot adapted to register with a joint in a masonry wall or the like.

6. A stenciling hawk for use in the application of waterproofing grout to the joints of masonry walls or the like, which includes a grout-holding trough, a back-member extending upwardly from the grout-holding trough, the back-member being provided with an opening therein, flexible material on the back-member extending beyond two opposite edges of the opening in the back-member to leave an elongated opening through the back-member, the back-member including two beads for aligning the elongated opening in the back-member with a joint in a masonry wall or the like.

7. A stenciling hawk for use in the application of waterproofing grout to the joints of masonry walls or the like, which includes a grout-holding trough, a back-member extending upwardly from the grout-holding trough, the back-member being provided with an opening therein, flexible material on the back-member extending beyond two opposite edges of the opening in the back-member to leave an elongated opening in the back-member, the back-member including means for aligning the elongated opening in the back-member with a joint in a masonry wall or the like.

8. A stenciling hawk for use in the application of waterproofing grout to the joints of masonry walls or the like, which includes a grout-holding trough, a back-member extending upwardly from the grout-holding trough, the back-member being provided with an elongated opening therein and including means for aligning the elongated opening in the back-member with a joint in a masonry wall or the like.

9. A stenciling hawk for use in the application of waterproofing grout to the joints of masonry walls and the like, which includes a grout-holding trough, a back-member extending upwardly from the grout holding trough and provided with an elongated opening therein adapted to register with a joint in a masonry wall or the like.
